UNITED STATES PATENT OFFICE.

WILLIAM H. MULLINS AND WILL C. HARE, OF SALEM, OHIO.

FIREPROOF WINDOW.

No. 825,002.

Specification of Letters Patent.

Patented July 3, 1906.

Application filed December 28, 1904. Serial No. 238,625.

To all whom it may concern:

Be it known that we, WILLIAM H. MULLINS and WILL C. HARE, residents of Salem, in the county of Columbiana and State of Ohio, 5 have invented a new and useful Improvement in Fireproof Windows; and we do hereby declare the following to be a full, clear, and exact description thereof.

Our invention relates to fireproof windows 10 for use in fireproof buildings and the like; and its object is to provide a window construction which will effectively withstand the heat in case of fire.

Window-frames have heretofore been made 15 with metallic sashes and with the glass held therein by means of the ordinary putty usually employed by glaziers for setting the glass with wooden sashes. When subjected to intense heat, as in the case of a conflagration, 20 the oil in the putty will burn out, and thus cause the same to disintegrate, breaking the bond or seal around the glass, leaving it unsupported, permitting the entrance of air, causing a collapse of the window and the entrance of flame.

The object of our invention is to provide a fireproof window which is not subject to the above difficulties and which is able to resist the flame and heat in case of conflagration, so 30 preventing serious damage liable to occur where the window collapses and permits the entrance of the flame.

To these ends the invention consists, generally stated, in the fireproof window formed 35 of a wrought-metal sash rolled or pressed, having a seat or recess, a wire-glass sheet within such recess, and a non-inflammable or fireproof cement setting the wire-glass sheet in the sash, so that the wire-glass sheet will 40 be held firmly within the wrought-metal sash, and the heat in case of conflagration will act to vitrify the cement and unite it both with the sash and glass, and thereby hold the glass within the sash and enable it to resist both 45 heat and pressure.

In the accompanying drawings, Figure 1 is 50 an elevation of a window constructed according to our invention; and Fig. 2 is a section, on an enlarged scale, taken on the line 2 2, 55 Fig. 1.

The sash of the window embodying our invention is formed of wrought metal, being preferably formed of sections bent from sheet metal and properly secured together.

As illustrated, it comprises the metallic stiles

1, bottom rail 2, top rail 3, and, if necessary, both horizontal and vertical muntins, depending upon the size and number of panes of glass contained therein. The rails, stiles, and muntins which are employed are provided 60 with seats or recesses 6, which are preferably grooved, as illustrated, in which the wire-glass sheets are set by the cement, the grooved seats inclosing the same and giving greater support to the cement holding the 65 glass sheet to place. The wire-glass is formed of a body of glass having embedded therein a wire mesh 8, which strengthens the glass and prevents the same from breaking or, even if it cracks, prevents the pieces from falling out, 70 such glass being well known in the market. The glass sheet having been seated in the grooved recess of the wrought-metal sash, it is sealed therein by a suitable or non-inflammable or fireproof cement filled within the 75 recess, preferably on both sides of the glass sheet and holding it firmly therein. For this purpose we employ a fireproof or heat-resisting cement, such as asbestos cement, the principal ingredient of which is asbestos, 80 or magnesia cement, the principal ingredient of which is magnesia, either of which cements is refractory and not affected by fire, the cements being united by suitable binders which will not burn out under intense heat. One 85 essential characteristic of the cement is that while holding the wire-glass sheet to place at ordinary temperatures under intense heat, as in the case of a conflagration, it will become vitrified to both the glass sheet and the body 90 of the wrought-metal sash, the heat suitably uniting the glass to the sash through the cement more firmly than when subjected to ordinary temperatures and where the sheet is simply held by the ordinary binding effect of 95 the cement. The cement filling or sealing is indicated at 10.

When a window embodying the invention is in use, it can be subjected to very intense heat without injury and is also able to resist lateral pressure—such, for example, as where a heavy stream of water is thrown upon the same when at a high heat. While the sheet is held to place by the cement sealing it within its seat and entrance of air at ordinary 105 temperatures is thereby prevented, the high heat developed in case of conflagration first acts upon the fireproof cement filling around the glass sheet and within its seat and causes the same to be vitrified both to the glass sheet 110

and to the wrought-metal frame, thus effectively maintaining the seal between the sash and glass even at such high heats and sustaining the glass sheet against lateral strain or pressure—for example, in the case of a heavy stream of water thrown upon it—holding the edge of the sheet firmly within its seat even though the body of the sheet is rendered plastic under the high heat to which it is subjected, while as the edges of the wire mesh embedded in the glass are thus held within the seat the entire sheet of glass is enabled to resist lateral pressure, and if the sheet becomes cracked under the heat the whole sheet will be held to place within its frame. As a consequence no opening will be formed through which the flame or heated air and gases may pass and the window will not collapse, and it thus provides a thorough protection from fire.

It will of course be understood that details of construction of the sash itself are imma-

terial and may be varied within the bounds above stated.

What we claim is—

1. A fireproof window formed of a wrought-metal sash having a seat or recess for the glass, a sheet of wire-glass seated therein, and a filling of fireproof cement seating the wire-glass within the recess. ²⁵

2. A fireproof window formed of a wrought-metal sash having a grooved seat or recess for the glass, a sheet of wire-glass seated therein, and a filling of fireproof cement seating the wire-glass within the grooved recess. ³⁰ ³⁵

In testimony whereof we, the said WILLIAM H. MULLINS and WILL C. HARE, have hereunto set our hands.

WILLIAM H. MULLINS.
WILL C. HARE.
